UNITED STATES PATENT OFFICE.

GEORGE W. STITZER, OF MAHANOY CITY, PENNSYLVANIA.

COLLAPSIBLE SHIPPING CASE.

Application filed March 16, 1921. Serial No. 452,890.

To all whom it may concern:

Be it known that I, GEORGE W. STITZER, a citizen of the United States, residing at Mahanoy City, in the county of Schuylkill, State of Pennsylvania, have invented certain new and useful Improvements in Collapsible Shipping Cases; and I do hereby declare the following to be a full, clear, and exact description of the invention, such as will enable others skilled in the art to which it appertains to make and use the same.

The object of the invention is to provide a comparatively simple shipping case of the collapsible type wherein the several elements representing respectively the top, bottom, side and end walls may be disconnected and stacked in parallel relation for return shipment or transportation in compact bundles or packages to minimize freight costs; and at the same time to provide a receptacle for the purpose and having the general characteristics indicated wherein, when set up, there is provided a container sufficiently rigid to adapt it to contain relatively heavy articles and withstand the rough usage to which such packages are subjected in freight and express handling, and particularly whereby the corners or joints are reinforced to guard against relative angular displacement of the adjoining walls; and with these and related and subordinate objects in view, the invention consists in the construction, combination and relation of parts of which a preferred embodiment is shown in the accompanying drawings wherein:

Figure 1 is a perspective view of a case embodying the invention, set up and closed ready for transportation.

Figure 2 is a longitudinal sectional view of the same.

Figure 3 is a horizontal sectional view on the plane indicated by the line 3—3 of Figure 2.

Figure 4 is a detail vertical sectional view through one of the side bottom joints on the plane indicated by the line 4—4 of Figure 3.

Figure 5 is a detail view in perspective of the bottom member.

The case consists essentially of the top and bottom members 10 and 11, which are substantially similar in contour and construction and are identical exteriorly, the side members 12 and the end members or walls 13. The bottom member is provided parallel with its side edges and preferably

set back somewhat therefrom, with cross sectionally dove-tail or undercut guides 14 for the reception slidingly of cross sectionally wedge-shaped or dove-tail webs 15 on the lower edges of the side walls, said webs being insertible at either end of the guides or grooves, and the side walls are provided adjacent to their vertical end edges with similar guides or grooves 16, also undercut or dove-tail in cross section, for the reception of the dove-tail or cross sectionally wedge shaped webs 17 on the side edges of the end walls, said side and end walls being provided at their upper edges with outwardly turned flanges or lips 12^a and 13^a respectively.

In assembling the case, the side and end walls may first be slidingly interlocked by the fitting of the webs on the side edges of the end walls into the undercut or dove-tail guides or grooves 16 of the side walls, after which the bottom wall or member may be slidingly fitted to the lower edge of the side walls by the engagement of the guides or grooves 14 thereof with the webs 15 of said side walls, and to serve as a stop for the movement of the bottom member and at the same time close the joints between the lower edges of the end walls and the plane of the upper or inner surface of the bottom member, flanges 18 are carried by the upper surface of the latter, these stop webs being arranged for contact with corresponding surfaces of the end walls, as for example, the inner surface of one end wall and the outer surface of the other end wall as shown clearly in Figure 2.

The top and bottom members of the case are preferably provided with marginal exterior reinforcements 10^a and 11^a having countersunk registering openings 19 at the sides and ends of the case and exteriorly of the side and end walls thereof, for the reception of tie bolts 20 of which the heads and bolts are fitted respectively in said countersinks, and preferably these countersunk openings are further reinforced by wear plates 21 to provide for constructing the case, when desired, of wood or heavy cardboard or other like material not having the tensile strength of metal. The tie or retaining bolts preferably extend through registering openings 22 in the flanges or lips formed at the upper edges of the side and end walls.

It will be obvious from the foregoing de-

2. description that, upon the loosening and removal of the tie or retaining bolts the several members or elements of the crate may be readily disengaged to adapt them to be folded in parallelism in compact form for packaging and return shipment, and that when set up the peculiar construction of the interlocking complementary elements by which the edges of the end and side walls are jointed and are connected respectively with the bottom member, a rigid structure is effected which will readily withstand the rough usage to which such packages are ordinarily subjected in transportation.
15. What is claimed is:
1. A collapsible shipping case having separable top and bottom members and side and end walls engaged by sliding movement, the said top and bottom members being extended beyond the plane of the side and end walls and provided with marginal exterior reinforcements having countersunk openings, and retaining bolts received within the openings and having their opposite ends secured within the countersinks, the bottom member being further provided with transverse stop webs arranged for contact with the lower edges of the end walls.
  2. A collapsible shipping case having separable top and bottom members and side and end walls, the side walls being engaged with the bottom member by horizontal sliding movement and the end walls being engaged with the side walls by vertical slid-
- ing movement, the said bottom member being provided with transverse stop webs arranged for contact with the lower edges of the end walls, said top and bottom members being extended beyond the plane of the side and end walls and provided with marginal exterior reinforcements having registering openings, and retaining bolts inserted within the openings and secured therein, 40
3. A collapsible shipping case having separable rectangular top and bottom members and side and end walls, the bottom member being provided adjacent its side edges with parallel guides for the reception of the side walls by horizontal sliding movement, the said side walls being provided adjacent to their vertical edges with similar guides for the reception of the end walls by vertical sliding movement, the said bottom member being further provided with transverse stop webs arranged to contact with the lower edges of the end walls, the top and bottom members being extended beyond the plane of the side and end walls and provided with marginal exterior reinforcements having registering openings and retaining bolts inserted within the openings and secured therein, 50
- 55
- 60

In testimony whereof, I affix my signature, in the presence of two witnesses:

GEORGE W. STITZER.

Witnesses:

ANNA SEAGER,
H. L. JONES.
